UNITED STATES PATENT OFFICE

WILLIAM L. MOORE, OF JERSEY CITY, NEW JERSEY

DESIGN FOR A DECK OF PLAYING CARDS

Application filed October 15, 1930. Serial No. 37,260. Term of patent 14 years.

To all whom it may concern:

Be it known that I, WILLIAM L. MOORE, a citizen of the United States, residing in Jersey City, in the county of Hudson, State of New Jersey, have invented a new, original, and ornamental Design for a Deck of Playing Cards, of which the following is a specification, reference being had to the accompanying drawings, forming part hereof.

In the drawings:

Fig. 1 is a plan view of the cards in the spade suit.

Fig. 2 is a plan view of the cards in the heart suit.

Fig. 3 is a plan view of the cards in the diamond suit.

Fig. 4 is a plan view of the cards in the club suit.

Fig. 5 is a plan view of the joker.

In all the views the backs of the cards are plain or conventional.

I claim:

The ornamental design for a deck of playing cards as shown and described.

WILLIAM L. MOORE.
